(57) **CLAIM**

The ornamental design for a walking cane handle, as shown and described.

DESCRIPTION

FIG. 1 is a perspective view of the walking cane handle according to my design.

FIG. 2 is an end view of the walking cane handle of FIG. 1. FIG. 3 is an opposite end view of the walking cane handle of FIG. 1.

FIG. 4 is a side view of the walking cane handle of FIG. 1. FIG. 5 is an opposite side view of the walking cane handle of FIG. 1.

FIG. 6 is a top view of the walking cane handle of FIG. 1; and,

FIG. 7 is a bottom view of the walking cane handle of FIG. 1.

The broken lines in FIG. 7 are for illustrative purposes only and form no part of the claimed design.
